SHEARING MACHINE

Adam J. Hermansdorfer, Calumet City, Ill., assignor, by mesne assignments, to Republic Steel Corporation, Youngstown, Ohio, a corporation of New Jersey

Application March 31, 1927, Serial No. 179,957
Renewed June 28, 1933

15 Claims. (Cl. 164—48)

My invention relates to certain improvements in machines for cutting a strip or bar of metal having recurrent transverse ribs or projections into sections or lengths, and is particularly adapted for shearing such strips into tie-plates on which the projections form cross-shoulders against which the bases of the railroad rails abut when the plates are in track.

Tie-plates are rolled from iron or steel blooms or billets in long strips or bars which are then sheared into a plurality of separate plates, and when cross-shouldered plates are sheared from a strip having recurrent transverse projections which form the shoulders the successive cuts to produce plates of approximately the same length are made at uniform distance from the faces of the projections against which the rail abuts when the plates are in track. Prior to my invention shearing machines for thus cutting these rolled strips into cross-shouldered plates were provided with a stop which was located in a predetermined position on the machine adjacent the shear and constructed to yieldingly bear upon the shouldered side of the strip as the latter was moved step-by-step under it toward the shear and to be raised by a passing shoulder and then drop behind the vertical face of the shoulder so that when the direction of movement of the strip was slightly reversed the shoulder which had last passed under the stop would abut against it to position the strip in proper relation to the shear. Embodiments of this old type of machine are shown in the patents to McKee No. 863,204, dated August 13, 1907, and to Knaus No. 978,598, dated December 13, 1910. However, in these prior machines the shouldered strip or bar must be moved far enough forward after each cut to permit the shoulder to pass beyond the stop so that the latter can drop down behind it, and then the strip must be reversely moved to abut the vertical face of the shoulder against the stop, as described in the aforesaid patents, and at least the reverse movement of the strip is done by hand by men of the shear-crew. This forward and reverse method of positioning the strip limits the machine to shearing the strips after the latter have cooled, and also makes the operation of the machines slow as it requires care and accuracy of the operators, and the output is limited to the capacity of the operators to handle the strips or bars, which usually are rolled eighteen to twenty and sometimes thirty feet long and are very heavy. Also, as in these prior machines the forward movement of the strip

to enable a shoulder to pass the stop projects the free end of the strip beyond its proper line and it is necessary to manually retract the strip to proper position before making a cut, this requires stopping the shear and skipping one or more shear strokes when the strip is not properly positioned in time for the regular stroke of the shear; and in using these prior machines the preliminary cooling of the strips to enable the shear-crew to handle them and position them on the shearing-machine requires extra equipment and additional handling of the strips.

My present invention provides a machine of this general character which enables the strips to be sheared while either cold or hot, and is comparatively simple and inexpensive to operate and more efficient in use and of increased capacity or output than those which have been heretofore used. The main feature of my invention is an organization whereby a strip or bar of the character above described is automatically moved step-by-step through the machine and positioned at the end of its intermittent forward movements with its recurrent cross-projections in uniform relation with respect to the shear. Another feature is the provision of means whereby the position of the cross-projections is adjustable relative to the shear in order to cut different strips having differently spaced projections into sections of different lengths to afford a wide range of sizes of tie-plates.

To these ends the invention consists in the novel organizations and arrangements of parts hereinafter described and pointed out in the appended claims.

In the accompanying drawings showing a practical embodiment of my invention, Fig. 1 is a front elevation of the machine, certain parts being in section and others broken away or omitted for clearness of illustration; Fig. 2 is a similar view of a portion of the machine with certain parts in different positions; Fig. 3 is a front end elevation; Fig. 4 is a rear end elevation of a portion of the machine; Fig. 5 is a detail plan view with parts in section; Fig. 6 is a detail plan view of the strip-table; Figs. 7 and 8 are enlarged detail side views of the rear guide and front guide respectively for the strip-feeding carriage, and Figs. 9 and 10 are enlarged detail front and sectional views respectively of means to adjust the travel of the strip-feeding carriage.

In the practice of my invention, the upper shear knife 1 is mounted on a reciprocating slide 2 which is supported and guided on the machine head 3 and operated by an eccentric on a rotat-

60

110

ing shaft 4, and the stationary knife 5 is mounted on a die-block 6 on the machine base; these parts are organized and operated in any suitable manner customary in this type of machine. A table or bed 7 to support and guide the metal bar or strip 8 is mounted on the base flush with the knife 5 and in line with a mill-conveyer (not shown) which presents the strip or bar to the machine. The table 7 is provided with opposite side guides 9 which form a guideway for the strips; the receiving ends of the guides are beveled outwardly to form a flaring mouth for the leading ends of the strips, and one or both of the guides may be laterally adjustable by suitable means, such for example as the headed bolts 10 threaded into the table and passing through elongated slots 11 in the guides, to vary the width of the guideway for strips of different widths. One face of the strip 8 is rolled with recurrent cross ribs or shoulders which are located near the leading ends of the sections or lengths into which the strip is to be cut to form tie-plates, and the vertical walls of the shoulders against which the rails abut when the plates are in track face away from the knives as the strip is presented to the machine.

A pair of longitudinal stationary guides, designated generally by the numerals 12 and 13, is oppositely mounted at the sides of the machine; in the form shown each guide consists of a pair of bars 14 and 15 of suitable length which are bolted together near their ends in spaced relation to provide elongated guideways 16. The front guide 12 is supported by an elongated bracket 17 depending from the head 3 and fastened to its upper bar 15, and the rear guide 13 is supported by an elongated bracket 18 extending upwardly from the block 6 and fastened to its lower bar 15. These guides extend from adjacent the knives toward the feeding-in or front end of the machine a distance equal to the length of a plurality of the sections or plates of the strip 8, and the guideways 16 are in a horizontal plane above the path of travel of the strip. The ends of the guide bars are connected by cross-pieces 19, the outer one of which is adjustable lengthwise of the guides, as by headed bolts 20 passing through elongated slots 21 in the bars. A strip-feeding carriage 22 reciprocates in the guides; in the form shown the carriage is a rectangular skeleton frame composed of inner and outer cross-pieces 23 and 24 and connecting side-pieces 25 whose edges are reduced to form runners to travel in the guideways 16. A cross-rod 26 is mounted in the side-pieces adjacent the cross-piece 24, and one end of the strip-pusher 27 is carried by this rod. The pusher consists of a metal plate, preferably divided at its free end, which extends forwardly and downwardly underneath the inner cross-piece 23 and rests upon the strip 8 when the latter is in position in the machine. The pusher may have pivotal motion on or with its rod 26 and so rest by gravity on the strip, or it may be rigidly mounted and so act as a spring arm; in either case it yieldingly rests on the strip, and the cross-piece 23 acts as a stop to limit its upward movement and prevent its being thrown up out of operative relation to the strip. The side-pieces 25 carry opposite wrist-pins 28 on which the inner ends of opposite side-rods 29 are pivotally mounted; these rods preferably are formed in sections connected by adjusting turn-buckles 30 to compensate for or take up any wear on the pusher and to vary the length of its throw or stroke, and are connected at their outer ends

to the lower end of a rocker-frame comprising an opposite pair of rocker-arms 31 keyed on the ends of a short cross-shaft 32 journaled in a bearing 33 on a bracket 34 on the head 3. One of the arms 31 extends upwardly and is pivotally connected by an adjustable link 35 to a crank-pin 36 carried on a disk 37 fixed on the shaft 4 which operates the knife-slide 2.

A strip-gauge 38 in the form of a flexible metallic plate is attached at its outer end to the cross-piece 19 of the carriage-guide and extends inwardly under the carriage with its free end between the sections of the pusher 27 and in line therewith when the latter is at the end of its inward or feeding stroke. The free end of the gauge bears on the strip 8 and rides over its shoulders as the latter are successively moved under it to position adjacent the shear, and snaps down behind each shoulder when the latter is so positioned to act as a stop to prevent recession of the strip, as for example by the action of the shear upon it and by vibration of the machine. It is so mounted and positioned that it presses down to hold the strip 8 from bending or tilting upwardly when the reciprocating knife 1 acts upon it.

A retracting bumper 39 is located at the rear end of the machine in the path of travel of the strip 8 and at a sufficient distance from the shear to permit the free end of a plate to register with it when the shoulder of a succeeding plate is in position adjacent the shear. The bumper is yieldingly mounted, and in the form herein shown it is carried on the downwardly projecting arm 40 of an angular lever 41 which is pivoted as at 42 on the bracket 34 and carries a counter-balance weight 43 at its free end. A chain 44 is connected at its ends to the outer end of the lever 41 and an arm 45 projecting from the head 3 to adjust the position of the bumper, as by adjusting the screw-eye 46 the position of the bumper toward and away from the shear can be adjusted. The bumper is not necessary when the strip rests on a flat or plain table such as shown as the frictional resistance between them will prevent the strip from moving beyond the stroke of the pusher 27, which itself properly positions the strip so that its cuts are at uniform distance from its shoulders; but the bumper is used when the strip rests on a table, such as a roller-table, which affords insufficient frictional resistance to prevent its movement by momentum beyond the desired position, and in such cases the bumper opposes such movement and retracts the strip to proper shearing position against the stop-gauge 38. The position of the bumper can be adjusted to correspond with the adjustment of the stop 38 to co-operate with shoulders differently spaced from the shoulder-ends of the plates as hereinafter described.

In the operation of the machine, when the shaft 4 is rotated and a strip 8 is positioned on the table 7 with its leading shoulder in the range of travel of the pusher 27, on the outer movement of the carriage 22 the pusher rides over the shoulder and drops behind it, and on the inward movement of the carriage toward the knives the pusher engages the vertical face of the shoulder and feeds the strip forward to bring the shoulder to the position shown in Fig. 2, where it is engaged by the gauge 38 and the strip is trimmed by the knives cutting off its scrap end. The parts are co-ordinated so that after the trimming cut is made as shown in Fig. 2, the pusher reciprocates outwardly and inwardly between

successive strokes of the knife 1 and successively moves the shoulders of the succeeding plate-sections of the strip beyond the knives and positions the strip in advance of each cutting stroke so that each plate is severed from the strip at its non-shouldered end as shown in Fig. 1. The pusher is a rigid unyielding element and so applies its power uniformly on all the shoulders on a strip being sheared, thereby avoiding any differences or irregularities in the step-by-step movements of the strip due to variations in its weight and resistance caused by changes in its length as it is shortened by plate-sections being successively sheared from its leading end. The cuts of each strip are made at uniform distance from its shoulders, so that practically the plates produced from the same strip are of uniform length and their shoulders are located at uniform distance from their ends. The severed plates drop upon a conveyor (not shown) by which they are carried to a spike-hole punching machine so that they can be punched while hot. While the spacing of the shoulders from the shoulder-ends of tie-plates is substantially uniform on finished plates of the same length, it is customary in the construction and use of tie-plates to vary the distance of the shoulders from the shoulder-ends of the plates in accordance with different lengths of plates, which in turn vary according to the size of the rails with which they are to be used; the shoulders on relatively long plates are farther from the shoulder ends than on shorter plates. One of the advantageous features of my invention relates to co-ordination of the strip feeding and cutting operations so that different strips having differently spaced shoulders may be cut on the same machine into plates of appropriate lengths for various sizes of rails. To accomplish this purpose the throw or range of movement of the strip-pusher is adjusted and fixed by devices which co-ordinate it with the different shoulder-spacings on strips for different lengths of plates. This may be done by adjusting the arms 29 as described, or the crank-pin 36 may be mounted for radial adjustment on its operating disk 37 and locked in different positions thereon by suitable means which regulate the extent of throw of the rocker-frame and consequently the travel of the carriage; by setting the crank-pin toward or away from the axis of the shaft 4 the throw of the rocker-arms may be varied to lengthen or shorten the stroke or travel of the strip-pusher. In the practical embodiment here shown, the disk 37 is provided with an open-end undercut radial slot 47, a spacer-block 48 of corresponding cross-sectional contour and of appropriate length in relation to the length of the plates is seated in the slot, and the crank-pin 36 is provided with a base 49 which also is of corresponding cross-sectional contour to seat in the slot against the outer end of the block, and these parts are held in the slot by a tap-bolt 50 which is adjustably carried in line with the slot by threaded engagement with a cap 51 removably bolted as at 52 to the disk, the tap-bolt being locked in position against the base 49 by a set-nut 53. It is obvious that the spacing blocks 48 may be provided with integral crank-pins 36 if desired. The blocks 48 are made of different shoulder-spacings on strips for different lengths corresponding in scale with different lengths of tie-plates, and when it is desired to produce plates of any given length the appropriate block and the crank-pin are fixed in the slot 47 as above described. In rolling tie-plates the recurrent pat-

tern of each finishing pass corresponds with the desired length of the plates and so normally produces shoulders at uniform intervals along a strip, and when this strip is presented to the machine having the operative stroke of its pusher adjusted for these intervals the strip will be cut into plates of uniform length and having their shoulders uniformly spaced from their shoulder-ends. Also, if shoulder-spacings vary slightly on the same strip or on different strips coming from the same roll-pass or from different similar passes, as frequently occurs from inequalities in the rolling process, the pusher will move the successive shoulders to the same position relative to the shear as its rearward travel or stroke is longer than the normal spacing between the shoulders as shown for example in Fig. 2 and compensates for such variations; the pusher positions all shoulders on strips of the same pattern at substantially the same distance from the shear regardless of such variations in their spacing on the strips. Also, as the feed-stroke of the pusher is adjustable it can be set to similarly act on different strips having differently spaced shoulders to be cut into plates or sections of relatively short or long lengths with their shoulders spaced respectively nearer to or farther from their shoulder-ends. The gauge 33 is adjusted by setting the crosspiece 19 toward or away from the shear so that it co-operates with shoulders spaced nearer or farther from the shoulder-ends of the plates according to the different lengths of the latter.

By my invention any strip of such cross-shouldered plates is automatically moved through the machine step-by-step, and positioned at the end of each intermittent feeding movement with a projection at proper distance from the knives to ensure the cuts being made at uniform distance from the projections. All the feeding and positioning operations are performed by the machine, so that the strips can be sheared as they come at red heat from the rolls, and hence the severed plates can also be punched while hot. This not only increases the output, as the time consumed in positioning the plates by hand is saved, but it extends the life of both the shearing and punching machines as hot shearing and punching reduce the strains and wear of the machines. Also, the machine has increased capacity and a wider range of production as it automatically feeds and positions strips of plates having their shoulders at different distances from their ends.

The cross-shoulders on tie-plates are of different designs and contour but always have a wall for the rails to abut against, and in using my invention the strip-pusher and stop may be suitably constructed and arranged to co-operate as described with any such shoulders. Other changes in form and arrangement of various parts may be made without departing from the scope of my invention.

I claim:

1. In a machine for shearing metal strips having a series of recurrent projections; the combination of a shear, and a strip-feeder comprising a carriage reciprocating toward and away from the shear above the strip being operated on and a gravity-latch pivoted on the carriage and constructed to ride over a projection of the strip when the carriage moves away from the shear and engage said projection as it moves toward the shear and move the strip step-by-step through the shear and position the successive projections in the same spaced relation to the shear;

2. In a machine for shearing metal strips having a series of recurrent projections, the combination of a shear, a stop arranged adjacent to the shear and constructed to successively engage the rear faces of the projections of the strip being operated on and automatically movable from and into the path of movement of the projections, and a reciprocating strip-pusher constructed to successively engage the projections and move them into position to engage the stop. 80

3. In a machine for shearing a metal strip having a series of recurrent projections, the combination of a shear, a strip-pusher reciprocating toward and away from the shear, and a stop located in fixed relation to the shear, the pusher and stop being constructed to ride the projections on the strip being operated on and successively engage said projections. 85
- 15 20 25 30 35 40 45 50 55 60 65 70 75
4. In a machine for shearing a metal strip having a series of recurrent projections, the combination of a shear, a strip-pusher reciprocating toward and away from the shear, a stop located in fixed relation to the shear, the pusher and stop being constructed to idle over the projections on the strip being operated on and successively engage said projections, and a bumper in the path of travel of the strip beyond the shear. 90
- 20 25 30 35 40 45 50 55 60 65 70 75
5. In a machine for shearing metal strips having a series of recurrent projections, the combination of a shear, a strip-pusher reciprocating toward and away from the shear and constructed to idle over one of the successive projections of the strip being operated on when it moves away from the shear and engage such projection as it moves toward the shear, a yielding stop located in fixed relation to the shear and arranged to permit the passage of the projections of the strip and engage the projections after their passage under the stop, and a yieldingly mounted bumper in the path of travel of the strip beyond the shear. 95
- 30 35 40 45 50 55 60 65 70 75
6. In a machine for shearing metal strips having a series of recurrent projections, the combination of a shear, a strip-pusher reciprocating toward and away from the shear and constructed to ride upon the strip being operated on and pass a projection thereon when it moves away from the shear and engage such projection as it moves toward the shear and feed the strip step-by-step through the shear, and adjustable operating rods to vary the travel of the pusher and position differently spaced projections on different strips at different distances from the shear for cutting relatively short and long strip-sections with their shoulders spaced relatively nearer to or farther from their shoulder-ends. 100
- 45 50 55 60 65 70 75
7. In a machine for shearing metal strips having a series of recurrent projections, the combination of a shear having a reciprocating knife, a rotating shaft to operate the knife, a strip-pusher reciprocating toward and away from the shear and constructed to move the strip being operated on step-by-step into the path of the shear, a rocker-frame to operate the pusher, a disk on the shaft having a radial seat for spacing-blocks of different lengths, and means positioned by said blocks to operate said frame. 105
- 60 65 70 75
8. In a machine for shearing metal strips having a series of recurrent projections, the combination of a shear, a strip-pusher reciprocating toward and away from the shear and constructed to move the strip being operated on step-by-step to the shear, means to vary the travel of the pusher, and a stop constructed to be fixed in adjustable relation to the shear and to permit the passage of the projections of the strip and engage each projection after its passage under the stop. 110
- 70 75
9. In a machine for shearing metal strips having recurrent projections, the combination of a shear, guides at each side of the shear, a strip-pusher reciprocating in the guides and constructed to successively engage the projections and move the strip being operated on step-by-step to the shear, means to vary the travel of the pusher, and a stop adjustably mounted on the guides and constructed to engage the projections when they are in position adjacent the shear. 115
- 80 85 90 95
10. In a machine for shearing metal strips having recurrent projections, the combination of a reciprocating knife, guides at each side of the knife, a strip-pusher reciprocating in the guides to successively engage the projections and move the strip being operated on step-by-step into the path of the knife, and a pressure stop adjacent the knife and constructed to permit the passage of the strip-projections and to bear on the strip and against the projections when the latter are in position in relation to the knife. 120
- 90 95
11. In a machine for shearing metal strips having a series of recurrent projections, the combination of a shear, a frame having a guideway adjacent the shear and above the strip being operated on, a carriage reciprocating in said guideway toward and away from the shear, a strip-pusher pivoted on the carriage to successively engage said projections, a resilient bumper in the path of the strip beyond the shear, and a strip-gauge consisting of a flexible metallic plate attached at its outer end to the frame and having its free end bearing against the projections when the latter are in position adjacent the shear. 125
- 100 105 110 115
12. In a machine for shearing metal strips having a series of recurrent projections, the combination of a shear, a guideway adjacent the shear, a reciprocating carriage traveling in said way and having a cross-piece, a strip-pusher pivoted on said carriage and extending below said cross-piece to successively engage said projections, a resilient bumper in the path of the strip beyond the shear, and a strip-gauge mounted on said way and extending under said carriage and terminating at substantially the line of the forward movement of said strip-pusher. 130
- 115 120 125
13. In a machine for shearing metal strips having a series of recurrent projections, the combination of a shear, a guideway adjacent the shear, a reciprocating carriage traveling in said way, operating means for said carriage including adjustable rods pivoted thereto, a strip-pusher pivoted on the carriage to successively engage said projections, a resilient bumper in the path of the strip beyond the shear, and a strip-gauge adjustably mounted on said way and extending under the carriage with its free end at substantially the line of the forward movement of said strip-pusher. 135
- 125 130 135
14. In a machine for shearing metal strips having a series of recurrent cross-shoulders, the combination of a shear, a reciprocating strip-pusher constructed to successively engage said shoulders, a strip-gauge constructed to successively engage said shoulders when they are in position in relation to the shear, a pivotally mounted bumper beyond the shear in the path of the leading end of the strip being sheared, and means to stress the bumper against said leading end. 140
- 130 135 140
15. In a machine for shearing a rolled metal strip having cross-shoulders spaced along its length into railway tie-plates each having a rail-seat and a cross-shoulder near the field-end of 145
